C. H. GOLLADAY
CASEMENT WINDOW FASTENER

Filed Oct. 16, 1923

Inventor
C.H.Golladay.

By Attorney

UNITED STATES PATENT OFFICE.

CLYDE H. GOLLADAY, OF LOS ANGELES, CALIFORNIA.

CASEMENT-WINDOW FASTENER.

Application filed October 16, 1923. Serial No. 668,886.

To all whom it may concern:

Be it known that I, CLYDE H. GOLLADAY, a citizen of the United States, residing at Los Angeles, in the county of Los Angeles and 5 State of California, have invented certain new and useful Improvements in a Casement-Window Fastener; and I do hereby declare the following to be a full, clear, and exact description of the invention, such as 10 will enable others skilled in the art to which it appertains to make and use the same.

This invention relates to a casement window fastener.

It is aimed to provide generally a novel, 15 durable, efficient and comparatively inexpensive device or means whereby casement windows may be secured positively in both open or closed position and may be also secured in adjusted positions intermediate the 20 open and closed position.

A particular object of the present invention is to provide a construction adapted for connection to a hinge by means of which the casement window is connected to its frame, 25 and with means of the device adapted to serve as the pintle of the hinge.

Another object is to provide a construction in which a pintle or stud is used having a leaf screw threaded thereto and attachable 30 to either the window or casing, and having a leaf capable of movement on the stud or pintle and attachable to either the window or frame, together with means, preferably threaded to the stud in order to bind the 35 leaves together and thereby hold the window locked.

Additional objects and advantages will become apparent from a consideration of the 40 description following taken in connection with the accompanying drawings illustrating an operative embodiment.

In said drawings:—

Figure 1 is a view showing the invention 45 in front elevation and in connection with a casement window and its frame, the latter part being shown fragmentarily;

Figure 2 is a view taken on the line 2—2 of Figure 1;

Figure 3 is a sectional view taken on the 50 line 3—3 of Figure 2, and

Figure 4 is a detail view showing the leaves detached with their engaging surfaces uppermost.

Like reference characters designate like or 55 similar parts in the different views.

Referring specifically to the drawings, A

designates a casing for a casement window B, both parts being conventionally and fragmentarily shown and the window is adapted for pivotal connection to the frame by means 60 of a hinge C. This hinge has leaves D suitably fastened one to the frame and one to the window and the leaves have interfitting aligned barrels as at E in the usual manner of hinges.

In carrying out the present invention, the usual pintle or the like which is disposed in the barrels E, is removed and a longer pintle or stud as at 10 is used in lieu thereof and which pivotally connects the leaves of the 70 hinge C in the same manner as the usual pintle of that hinge.

Pintle or stud 10 is screw threaded for a distance downwardly from its upper end as at 11. A leaf as at 12 is fastened in any 75 suitable manner as by screws 13, for instance to the frame A and has a plate 14 at one end thereof disposed in a horizontal plane and having screw threads in a bore 15 whereby the same is threaded to the 80 stud or pintle 10 and serves to maintain the latter in place and particularly to prevent downward displacement thereof. A companion leaf 13 is shown at 16, being suitably fastened as by screws 17 to the window 85 C and having a plate 18 at one end thereof adapted for disposition in a horizontal plane and to rest on the plate 14. As the window C usually is inwardly offset from the frame, the plate 16 has an offset portion 19 properly positioning the plate 18. A nut 20 is threaded to the screw threads 11 and preferably has wings as at 21 to facilitate manipulation of the nut.

The stud 10 passes through a bore 22 95 of plate 18 and said bore is preferably enlarged with respect to the stud so as to avoid binding or interfering contact with the screw threads thereof and in order that the plate 18 may be capable of freely 100 swinging about the stud 10 as a pivot when the nut 20 is loosened. Plate 14 has a securing element at 23 providing a spherical surface projecting above its upper surface and adapted for selective reception in recesses 105 24 provided in the under surface of the plate 18. The spherical surface of the element 23 may be afforded in any manner desired for instance by having said member 23 a ball or sphere as shown sunk and swiveled into the plate 14 and being retained in the plate as the latter is crowded about the ball 110.

above the horizontal plane passing through its axis.

In use when the window B is to be swung, the nut 20 is loosened, which releases the binding engagement between the plates 14 and 18 and permits the plate 18 to elevate slightly, due to the usual swinging of the window, in view of the ball 23. The recesses 24 will successively engage the ball 23 and when the window is in the proper position, either open, closed or intermediate position, the ball 23 will be located in one of the recesses 24 after which the nut 20 is tightened and the plates 14 and 18 secured together in binding relation and against accidental turning in view of the extension of ball 23 into recesses 24.

Attention is called to the exceedingly compact arrangement whereby the invention is disposed relatively close to and cooperates with one of the hinges of the window.

It is also to be considered that the casement window is shown by way of example and that the invention is capable of use generally where hinges are employed and a window, door or other part is mounted to swing with respect to a frame or equivalent part.

Having thus described the invention, what I claim is:—

1. A securing means of the class described, in combination with a hinge using a pintle, a stud applicable to the hinge in lieu of the

pintle, leaves extending from the stud for connection to a frame and member which moves relatively to it, the stud constituting the axis for one of the leaves, and means to secure said leaves together. 35

2. A securing means of the class described, in combination with a hinge using a pintle, a stud applicable to the hinge in lieu of the pintle, leaves extending from the stud for connection to a frame and member which moves relatively to it, the stud constituting the axis for one of the leaves, and means to 40 secure said leaves together, one of said leaves being screw threaded to said stud. 45

3. A securing means of the class described, in combination with a hinge using a pintle, a stud applicable to the hinge in lieu of the pintle, leaves extending from the stud for connection to a frame and member which moves relatively to it, the stud constituting the axis for one of the leaves, and means to 50 secure said leaves together, one of said leaves being screw threaded to said stud, interengaging securing means between the leaves, and a nut threaded on the stud to bind the leaves together. 55

In testimony whereof I affix my signature in presence of two witnesses. 60

CLYDE H. GOLLADAY.
